UNITED STATES PATENT OFFICE.

CHARLES L. BUCKINGHAM, OF NEW YORK, N. Y.

AUTOMATIC PRINTING-TELEGRAPH.

SPECIFICATION forming part of Letters Patent No. 737,203, dated August 25, 1903.

Application filed February 1, 1900. Serial No. 3,606. (No model.)

To all whom it may concern:

Be it known that I, CHARLES L. BUCKINGHAM, a citizen of the United States of America, and a resident of the city, county, and State 5 of New York, have made a new and useful Improvement in Automatic Printing-Telegraphs, of which the following is a specification.

In United States Letters Patent No. 544,348, 10 of August 13, 1895, applied for by Emil Germann and myself, is shown a system upon which the present invention is an improvement, in that it contemplates the printing of figures in addition to the letters of the alphabet, punctuation-marks, &c.

It would obviously be possible to increase the number of characters to be printed if eight reversals of current for each were employed. In fact, if four Morse pulses or eight 20 reversals were transmitted for each character sixty-four characters might be placed on the type-wheel, thus affording opportunity for many more than the necessary number of letters, punctuation-marks, and figures; but 25 by this plan the speed of transmission would be so far reduced that only three characters could be transmitted, where four are sent if only six reversals for each are employed.

My present invention has for its object a 30 plan of transmission whereby letters and punctuation-marks may be sent by six reversals, precisely as by the system set forth in said former patent, and by which figures may be transmitted in substantially the same 35 time that is required for sending letter characters. To this end an additional ring of type characters is added to the type-wheel shown in said patent, but for the figure characters of the added ring eight reversals for 40 each must be employed.

In adapting my system to print figures as well as the letters of the alphabet and punctuation-marks, as will hereinafter be shown, the perforating-machine for preparing messages 45 remains practically unchanged in its essential features, while to the printer only the merest additions have become necessary.

Referring to the drawings, Figure 1 is a diagram of circuits and some of the essential 50 parts of my printing-receiver. Fig. 2 is a diagram of circuits and parts of the printer to which the present invention more partic-

ularly relates. Fig. 3 represents the type-wheel of my improved printer with arms, links, and levers by which the type-wheel is 55 given rotation and lengthwise movement for setting it in its several positions for printing. Fig. 4 shows a development of the peripheral surface of the type-wheel and particularly the added ring of figures and the ring of 60 type, including the blank, whose normal position is above the platen of the printer. Fig. 5 shows the type-wheel and the arms, links, and levers of the printer to which the present improvement is added. Fig. 6 is a 65 detail showing means whereby the type-wheel may be moved lengthwise and rotated at the same time. Fig. 7 shows the alphabet and punctuation-marks in perforated characters, together with dots, dashes, and spaces, as 70 said characters would appear when reproduced by the Wheatstone recorder. Fig. 8 represents the figures of my code both as they appear in the perforated transmitting-tape and as they are reproduced in dots, dashes, 75 and spaces by the Wheatstone recorder. Figs. 9 and 10 are diagrams showing modifications of apparatus and circuits represented in Fig. 1.

In Figs. 1, 2, 9, and 10 are represented the 80 sunflower arrangement of Patent No. 544,348, in which are employed a differentially-wound escapement-magnet *p*, an escapement-wheel *a*, and pallets *b*, under the action of which the sunflower-shaft is permitted to rotate step 85 by step at each main-line reversal, while upon the same shaft is a wheel *c*, having one-third as many teeth as *a*, which serves both to put the sunflower at unison at the end of each word, as set forth in Patent No. 544,348, and 90 to move contact-arms *d e f g h i*. In the normal operation of the sunflower apparatus wheel *c* moves the space of one tooth for each letter transmitted, and this movement is accomplished by six main-line reversals of 95 current or by three positive and three negative pulses. The long negative pulse, which terminates each letter of my alphabet, energizes the polarized unison-magnet *n* in such manner that arm *l*, pivoted at *m*, is lifted 100 away from the teeth of wheel *c*; but under the action of a short negative or a positive pulse, long or short, the hook of arm *l* remains in position to arrest the teeth of *c*. Some or

all of the six reversals of each character may be prolonged, and whether it is one character or another that is transmitted is determined by the reversal or reversals that are prolonged. In the arrangement shown in Fig. 1 after arm *l* has been raised at the end of a character upon the first reversal of the following character wheel *c* next actuates arm *e* to close contact with wire 43, while the following reversals cause arm *f* to close contact with 44, *g* with 45, *h* with 46, and *i* with 47, and finally the sixth reversal causes arm *d* to close contact between wire 17 and wire 18 and to thereby form circuits, which are completed by armature-tongue 19, contact 21, through relays *s* and *t*, included, respectively, in branches 24 and 23. If the sixth pulse were a prolonged negative current, relays *s* and *t* would respond to effect printing, as is the case in transmitting letter and punctuation characters; but in the transmission of the figure characters "2" to "9" the sixth pulse is so short in duration that although circuits are closed through *s* and *t* the latter will not respond. When, however, the seventh or long positive or dash pulse which follows is passed to line, the synchronizing-arm *l* still holds wheels *c* against rotation, and arm *d* preserves contact between wires 17 and 18; but under the action of the positive pulse the tongue 19 of main-line relay *r* is thrown against stop 20, and a circuit is completed through wire 22, in which is inserted the setting-coil of relay 6, wire 48, one of the two coils of relay 7, and resistance 9. And, again, at the end of the figure characters the eighth or the prolonged negative pulse, following the positive, throws the tongue of relay *r* to the right, once more establishing circuits including wire 18, contact 21, and the two wires 24 and 23, one including the sixth-pulse relay *s* for closing circuits to magnets *x w v u*, which actuate the escapement-dog, feed-ribbon, and press apparatus of the printer, while the other includes relay *t*, termed the "resetting-relay," for closing the circuits 40 42, by which the tongues of relays 1 2 3 4 5 6 7 are thrown to their back positions at the end of each character transmitted.

As shown in Fig. 1, the setting-coils of relays 1 2 3 4 5 are respectively joined with wires 47 46 45 44 43, and these circuits are successively closed by sunflower-arms *e f g h i* at each step of rotation. If only short reversals or pulses are sent over the main line, the movements of tongue 52 of relay *q* are so rapid that the neutral differential relay *o* will not be sufficiently energized to move its armature, although wheel *a* at the time is allowed to rotate under the action of the differential polarized magnet *p* and escapement-anchor *b*; but upon the prolongation of a main-line pulse a current will flow through either 53 or 54 a sufficient length of time to enable *o* to attract its armature and close a circuit including wires 50 49 and bracket *j*, with which arms *e f g h i* are electrically

connected; but bracket *k*, upon which *d* is mounted, is insulated from *j*. Thus as *o* attracts its tongue a local circuit is closed from *aa* to *bb* through that one of the selecting-relays whose circuit is at the moment closed by arm *e, f, g, h, or i*, and thereby the tongue of such relay is moved to the right, breaking one contact and closing another in the operation of setting the type-wheel. The setting-magnets controlled by relays 1 to 5 are 11 12 13 14 15. From the foregoing it is obvious that during the first five reversals of current some one or more or all of said magnets may be brought into action for each character transmitted and that the operation of printing may be effected during the sixth, at which time a tooth of wheel *c* causes arm *d* to join wires 17 and 18. A sixth arm might be added to the series *e f g h i* for closing a circuit through the setting-coil of selecting-relay 6, but if this were done it would be necessary to give the sunflower eight steps of rotation for each character transmitted and to employ for each eight current reversals instead of six. It is therefore desirable to employ the relay *r* and to actuate relay 6 through contact *d* while the sunflower is locked by arm *l*, for by this plan all letters of the code may be transmitted by six reversals, although eight are required for the numerals in the fifth ring of the type-wheel.

In the arrangement of Fig. 1 a wire 33 leads from the pole *aa* of the local battery to the tongues 34 35 36 37 38 39 of the selecting-relays 1 2 3 4 5 6, thence through the setting or resetting sides of the adjusting-magnets, according to the positions of said tongues, and thence to the negative pole *bb*. At the end of each character transmitted relay *t* is brought into action, thereby closing tongue 41 to establish a circuit from *aa* by 40, 41, and 42 through the resetting-coils of selecting-relays 1 to 6, whereby such of the tongues of said relays as may have been moved to front position in the transmission of a character are reset to their back positions. A seventh relay, in all respects like the six selecting-relays, is employed for preventing the operation of the press-hammer during the transmission of a space character—that is to say, where the paper sheet upon which the message is printed is to be fed to make spaces between words. During such a transmission no current reaches the setting coils of the selecting-relays; but in the transmission of any one of the printed characters some one or more of said setting-coils will be energized. It follows, therefore, that if the circuits of said setting-coils were united into one circuit, as here shown, a relay, as 7, might be operated to close the press-circuit when a character to be printed was transmitted. The multiple setting-coils of the selecting-relays 1 to 6 are united into one conductor 48, within which is included the setting-coil of relay 7, while its resetting-coil is placed in series with those of the se-

lecting-relays in conductor 42. Thus if a character to be printed were transmitted the current sent to the setting-coils of whatever selecting-relays might be called into operation would also pass through the setting-coil of 7, thereby causing the tongue of said relay to close a circuit to press-magnet *u* by wires 10 28 25 and armature-tongue 26, while at the end of the transmission said tongue would be returned to its back position, thereby breaking the press-magnet circuit. The press-circuit is normally open at two points, and the same is always closed by relay *s*, whether for a space or character transmission, but the press-circuit is only closed at relay 7 upon the transmission of a character which is to be printed. This feature of invention I do not wish to claim herein, as it is the subject-matter of an application, Serial No. 3,611, filed February 1, 1900, by C. L. Buckingham and E. Germann. A further feature of the invention hereinbefore described, consisting of the setting and resetting coils of the selecting-relays, in combination with rheostats 8 and 9, I do not wish to herein claim, as the same forms part of the said Buckingham and Germann application.

In former arrangements it had been thought necessary to employ a rheostat in series with each setting-coil, but by the arrangement here shown the two rheostats obviously fulfil every purpose, particularly as current never passes through more than one setting-coil at a time.

From the organization of Patent No. 544,348 the relay *r* or its equivalent is entirely omitted, as are selecting-relay 6 and adjusting-magnet 16. They are included in my present arrangement in order that I may add a fifth ring of type and eight additional figure characters to the type-wheel.

In Fig. 7 I have shown an alphabet consisting of twenty-seven letter characters, with a comma, period, question-mark, dash, space-mark, and line-mark. These characters are all transmitted and printed by six reversals of current, as here indicated, and in this case each character is terminated by a long negative pulse, which, as already explained, serves to throw tongue 19 to its right-hand position upon contact 21, while at the same time arm *l* of the synchronizing device is lifted out of the path of the wheel *c*; but to print from the extra ring of type containing the figure characters "2, 3, 4, 5, 6, 7, 8, 9" eight reversals instead of six are employed for each, and as will be seen in Figs. 7 and 8 such figure characters are formed, respectively, by adding a Morse dash at the end of the space character and the letters "a, t, d, e, s, n, m"—that is to say, my figure "2" is formed by adding a Morse dash at the end of the space character of my alphabet, the "3" by adding a dash to the letter "a," the "4" by adding a dash to the letter "t," the "5" by adding a dash to the letter "d," the "6" by adding a dash to

the letter "e," the "7" by adding a dash to "s," the "8" by adding a dash to "n," and the "9" by adding a dash to "m." The characters "0" and "1" are the "O" and "I" 70 of my alphabet. Thus it is seen that in receiving those figure characters which are transmitted by eight reversals the sixth pulse is a short negative current, which is not sufficiently prolonged to lift the synchronizing-arm *l* or to permit the operation of relays *s* and *t* and that during the seventh long positive pulse forming the dash which follows, as well as during the sixth, the sunflower is held in a stationary position, and that during the 80 period of such dash the relay-tongue 19 is held against its stop 20, thereby allowing a current to be sent into relay 6, causing its armature-tongue 34 to move to front contact to actuate the sixth setting-magnet. Following the 85 terminal dash, however, of a figure character the tongue 19 is thrown upon contact 21, thus closing circuits through the sixth-pulse relay and resetting-relay *t*, whereby the dog, paper-feed, ink-ribbon, and press-magnets *x, w, v, u* are actuated and the tongues of the selecting-relays 1 to 7 are reset to their initial positions as if an ordinary letter character were being printed.

In the present instance the apparatus of 95 Fig. 3 for rotating the type-wheel is precisely like that shown in Patent No. 544,348, in which are employed the setting-arms 150 151 152, having separate and independent capacities for giving the type-wheel individual or collective movements. Thus assuming the wheel to normally rest at a zero position the setting-arm 150 serves to rotate it one letter-space, the arm 151 two, and the arm 152 four, while 150 and 151 working in succession would 100 rotate the wheel to the third position, 150 and 152 to the fifth, 151 and 152 to the sixth, and 150, 151, and 152 to the seventh. In this organization the arm 150 in its back position rests against stop 97, 151 against 99, and 152 105 against 100, while in their front positions they are respectively in contact with stops 96, 98, and 101. To the upper end of 150 is pivoted a longitudinal link 95, which is likewise joined with horizontal arm 94, the latter 110 being carried upon a fixed central pivot. The opposite end of 94 is joined with bar 92 by link 93. Bar 92 has a pivoted support upon the upper end of adjusting-lever 151. Again, the opposite end of 92 is joined with bar 86 115 by link 91, and to the latter is connected a plunger 85, carrying at its outer end a radial pin, which works in a spiral slot 84, formed in the shell of a hollow rotating hub, within whose opposite end projects a type-wheel 120 shaft 80, carrying a pin which works in a longitudinal slot 82, thus allowing a lengthwise movement of the wheel at the same time that it is rotated by plunger 85. The arm 86 is also pivoted to link 87 and link 87 to bar 88, 125 moving around a fixed pivot 89, while the setting-lever 152 is connected to the bar 88 by a

link 90. Thus as the bars 150 151 152 are moved during the transmission of a character the plunger 85 is pushed in and out of a central opening in the hub carrying the spiral slots 84, while the hub is held against longitudinal movement by a ball-bearing support, a groove for holding the balls of the bearing being shown at 83. Thus rotation is communicated to the type-wheel shaft by plunger 85 and the spiral slot, and thence by the radial pin, which is also free to move longitudinally in slot 82.

At the right of Fig. 3 is shown apparatus by which the type-wheel is given its lengthwise movement. As here shown the setting-levers 153 154 155 are in their back or normal position against stops 64, 62, and 60, while at their front position they come in contact with stops 65, 63, and 61. 79 represents the type-wheel, and 78 a thimble having conical radial holes, one for each character upon the type-wheel. By means of these holes as the type-wheel is set to its approximate position for printing a dogging-pin having a conical point is thrust into a corresponding opening to bring the type-wheel into a final and definite position. At the right and attached to the dogging-thimble is a spindle 73, which is free to have longitudinal movement for moving the type-wheel endwise and which is in such rotary relation with the type-wheel (see Fig. 6) that as the type-wheel is moved lengthwise it may be rotated by the apparatus already described from its opposite end. Lengthwise movement is imparted to the type-wheel as follows: Arm 153 is linked to lever 75, which is carried upon a fixed pivot 77, and 75 in turn is connected by link 71 to a lever 72, pivoted to 73, which is also linked at its opposite end to 74 and thus to a pivoted arm 70, which is carried upon the upper end of the setting-lever 154. At the opposite end of arm 70 is a link 69, connecting the same with an arm 68, turning about a fixed pivot 67, which is also connected by link 66 to setting-arm 155. By this means upon a prolongation of the fifth pulse of a character the type-wheel is moved by arm 153 one ring of type or one letter position to the right, while by the fourth pulse, which would actuate arm 154, the type-wheel would be moved two rings to the left. By moving both 153 and 154 the wheel would be moved two rings of type to the left and next one to the right, thus leaving it one ring of type to the left from its initial position. Again, by actuating arm 155 the wheel is moved the space of two type-rings to the right, or into such position as to bring the ring of figure characters over the press-pad. Thus it is seen that to bring the figure characters "3, 4, 5, 6, 7, 8, 9" over the press-pad the wheel should be first given such position of rotation as would be necessary to print the several letters in the space-ring and that in addition to such operation the setting-arm 155 must be actuated during the terminal dash.

of the character to move the wheel two spaces to the right.

For convenience of illustration I have shown in Fig. 1 two main-line relays *r* and *q*; but one such relay may be sufficient. Thus in place of *r* the relay *q* could be provided with an additional contact-arm working between front and back stops 20 and 21, or the arm *b* for controlling the escapement of wheel *a*, as shown in Fig. 9, may be made to serve the same purpose. In this case the wire 18 is joined with arm *b*, which during the long positive pulse at the end of a figure character would be joined with stop 20, thereby completing a circuit to the selecting-relay 6, while in its opposite position it would be joined with 21, thus completing the circuits to relays *s* and *t*. Various other means may be found as a substitute for the additional main-line relay *r*. For instance, as in Fig. 10, the synchronizer-arm *l* may be made to perform this function. In this case the wire 18 is connected to the synchronizing-arm, which under the action of long positive or short negative pulses is held against the lower contact 20, thereby closing a circuit from wire 18 to the selecting-relay 6, while under the action of the long negative pulse at the end of a character the synchronizing-arm is raised to contact 21, thereby establishing circuits from contact 20 to the sixth pulse-relay *s* and the resetting-relay *t*.

From what has preceded it will now be seen that the essential features of my plan for adding figures to my telegraph-printer consist, first, in the locking of the sunflower against rotation by a synchronizing-arm during the sixth and seventh pulses of a character, and, second, in an additional main-line polar relay *r* or its equivalent, whereby the local current, which otherwise would pass through relays *s* and *t* during the seventh or dash pulse to cause printing and the resetting of the selecting-relays, is diverted to a sixth selecting-relay for causing the figure-ring of the type-wheel to be moved lengthwise to a position over the platen. Not only does the relay *r* during the seventh or dash pulse serve to prevent the several operations of printing, the feeding of the paper sheet upon which the message is taken, and the resetting of the selecting-relays, but it serves to direct the local current during the eighth or last negative pulse to effect these results preparatory to the transmission of a succeeding character precisely as if it were a sixth terminal pulse used in printing letters rather than the eighth in printing numerals.

It is obvious that with three setting magnets or devices for securing lengthwise movement of the type-wheel eight different movements might be secured and that eight rings of type might be employed. In fact such an arrangement is shown in Fig. 12 of Patent No. 544,348; but, as has already been shown, a fifth ring of type is sufficient for printing the

ten digit characters. It would perhaps be a convenience if the type-wheel were provided with more than forty characters, but by adding only one ring of type the size and weight of the wheel are not materially increased nor are the figure characters, as they appear in the perforated tape, Fig. 8, materially lengthened over the letter characters shown in Fig. 7. In fact, I have succeeded in providing figures with only the addition to my printer of a fifth ring of type upon the type-wheel, an additional setting magnet or magnets 16 for moving the type-wheel, an additional selecting-relay for controlling said selecting-magnet, and an additional main-line relay *r* or its equivalent. Nor does the preparation of the figure characters, as shown in Fig. 8, require any substantial change in my perforating system. The "9," the longest figure character as it appears in the perforated tape, covers a space of nine central holes, which is no longer than the letter "&," and thus it is that the apparatus of the perforator, which has a capacity to feed the transmitting-strip a space covering nine central holes or any less distance, is adapted to control the strip in perforating the figure characters. It is also to be noted that the range of the punch-head of the perforator, which is sufficient for the letter "&," has a sufficient range for the figure characters—in other words, the eight pairs of punches that are necessary for preparing the letter "&," Fig. 7, are sufficient for the figure "9," Fig. 8. The only change required upon the perforator is the addition of such keys as are peculiar to the figures "2" to "9," as such characters are shown in Fig. 8.

What I claim, and desire to secure by Letters Patent, is—

40 1. A telegraph alphabet or code, in which a part of the characters are formed, each by a definite number of transmitted pulses, while each of the others is formed by a different definite number, the character of a letter, sign or figure being determined by prolonging, strengthening, or otherwise modifying one or more of said pulses.

2. In a printing-telegraph system, an alphabet or code in which the letters or other signs are each formed by a definite number of transmitted pulses, while the numerals, or parts of them, are each formed of a different definite number, the character of said letters, marks or numerals being determined by prolonging some one or more of said pulses.

3. In a printing-telegraph system, an alphabet or code in which its letters or other signs are formed each by a definite number of alternately positive and negative pulses, while the numerals, or a part of them, are each formed of a different definite number, the character of the letters, signs, or numerals being determined by prolonging some one or more of said pulses.

45 4. In an automatic printing-telegraph system, a perforated strip of paper for transmit-

ting messages in which some of the letters or other characters are each represented by a definite equal number of perforations, while other characters, as numerals, are each represented by a different definite number, whereby part of the characters of the code are transmitted by a succession of pulses of one definite number, while others are transmitted by a different definite number.

5. In an automatic printing-telegraph system, an alphabet or code in which the letters or other signs are each transmitted by six reversals of current, while the numerals, or some of them, are each transmitted by eight such reversals.

6. In an automatic printing-telegraph system, an alphabet or code which is represented in a perforated tape by six perforations for each of the letters or other signs and by eight for each of the other characters, as the numerals, or some of them.

7. In a printing-telegraph system, the combination of a type-wheel provided with letters, numerals and other signs, a sunflower or equivalent arrangement which is adapted to move six steps for each letter or other character, means for transmitting one electrical pulse or reversal for each step of movement, a locking device for holding said sunflower against rotation, and means for transmitting eight electrical pulses or reversals for each of the numerals, or some of them, means for releasing said locking device, a main-line relay *r* or its equivalent, and means controlled thereby for setting the type-wheel into position to print numerals during the seventh pulse, and to effect printing and other operations of the apparatus during the eighth pulse, at the end of each character.

8. In a printing-telegraph system, the combination of a type-wheel, a sunflower arrangement, a locking device for holding said sunflower against rotation except under the action of a prolonged pulse of one polarity at the end of each character, a relay *r* or its equivalent, which, during a pulse preceding the last of a character, controls apparatus for setting the type-wheel into position to print numerals, and which, during the last pulse of said character, serves to bring into action the printing apparatus and other operations of the printer following each impression.

9. In a printing-telegraph system, the combination of a sunflower-wheel *c*, locking device *l*, relay *r* or its equivalent, a type-wheel, an adjusting device 16, which is brought into action to set the type-wheel by said relay by the pulse of a character preceding the last, together with printing devices, paper-feeding and other apparatus which are brought into action by said relay during the last pulse of a character.

10. In a printing-telegraph, a type-wheel carrying five rings of type, two adjusting devices for setting said wheel to any one of four positions, a third adjusting device for setting

the wheel into its fifth lengthwise position, a
step-by-step sunflower arrangement, a lock-
ing device for holding the same against rota-
tion, a relay *r* or its equivalent for bringing
5 said third adjusting device into action by the
maine-line pulse next preceding the last of
each character, and for actuating the press

mechanism and feeding devices during the
last pulse of the series.

CHARLES L. BUCKINGHAM.

Witnesses:

JOHN C. SANDERS,
ROBT. F. DOYLE.
